Harper

(57) CLAIM

The ornamental design for a table, as shown.

DESCRIPTION

FIG. 1 is a perspective view of a table, showing my new design;

FIG. 2 is a front view;

FIG. 3 is a top view;

FIG. 4 is an end view; and,

FIG. 5 is a bottom view.

The broken lines are for environmental purposes only and form no part of the claimed design.
